GRAIN DOOR

Henry William Ethell, Erinview,
Manitoba, Canada

Application August 8, 1934, Serial No. 738,970

1 Claim. (Cl. 20—30)

The invention relates to improvements in grain doors and an object of the invention is, to produce a door for railroad freight cars which is simple in construction, will permit the loading of the cars with grain, such as wheat, oats, barley, etc., can be quickly opened at the terminal for dumping purposes and when not in use, conveniently stored under the roof of the car, readily accessible for further use.

10 A further object of the invention is, to construct the operating parts of the door as a permanent part of the freight car and such, that the door may be erected into place without requiring special tools.

15 A further object of the invention is, to construct the door in tiers of sections, the said sections having their upper and lower edges cut in complementary abutments, forming, when in use, a grain tight wall to prevent seepage and 20 permitting, due to the sectional construction, the stacking of the sections in a minimum of space when stored.

A further object of the invention is, to provide the car with door guides and a lock and the 25 lower section with connections such, that by the use of a crane or other lifting force, the door can be bodily lifted, either for a short distance and held by the lock for dumping purposes, or carried up to the storage position.

30 A still further object of the invention is, to loosely mount the sections on the door guides to permit them to turn at the upper corner when moving along the guides, and to construct the guides at a slight angle so that the said clearance is taken up on the bottom section, forcing it tight to the door posts, while the weight of the 35 grain is utilized to maintain the upper sections in a similar grain tight engagement.

With the above important objects in view 40 which will become more apparent as the description proceeds, the invention consists essentially, in the arrangement and construction of parts hereinafter, more particularly described, reference being had to the accompanying drawings in 45 which,

Fig. 1 is a fragmentary, vertical, longitudinal section taken through a freight car and looking at the inner side of the grain door.

50 Fig. 2 is a vertical, cross sectional view taken at 2—2, Fig. 1.

Fig. 3 is an enlarged, horizontal section taken at 3—3, Fig. 2.

55 Fig. 4 is a perspective view of an end of one of the door sections showing the shape of the

upper and lower edges and one of the guiding U bars.

Fig. 5 is a perspective view of the lower part of the door showing the hook connections for lifting it up.

In the drawings, like characters of reference indicate corresponding parts in the several figures.

A freight car is generally indicated by the numeral 1 and comprises a floor 2 and sides 3. 10 The upper ends of the sides are fastened to a sill 4 which carries crossbeams 5 supporting the roof 6. The usual doorways 7 are provided on either side with door posts 8 and 9 extending between the floor and the sill. 15

On the sides of the door posts remote from the doorway, I fasten as by bolts 10, a pair of angle irons 11 and 12 which extend up the sides of the posts and then curve inward under the sill and terminate in a horizontal plane a short 20 distance within the car proper. It will here be noticed, that the angle irons at the floor level are slightly in from the inner edge of the door posts and that they extend upward at a slight slant until they are flush with the edge before 25 starting to curve.

A pair of channel irons 13 and 14 extend across the car at the doorways and are supported centrally from the crossbeams 5 by bolts 15. These channels are positioned between the 30 ends of the angle irons 11 and 12 on either doorway and are aligned therebetween, although they do not touch each other. The central part of the channels are provided with projecting webs 13' fastened to the base part of the channel irons and extending outward therefrom to a point level with the two opposing flanges. This divides the area between the flanges into two compartments 14' and 15'. These webs extend from the ends of the channels and terminate a 35 short distance from the bolts 15, leaving a vertical passage 16' for a purpose later described. 40

A grain door 16 is received against the inner sides of the door posts and comprises a plurality of sections 17 extending slightly more than 45 the full width of the door posts and carried one on top of the other. The upper part of each section presents a lengthwise extending tongue 18 on the outer edge and on the inner edge, from the bottom of the tongue, a downwardly sloping 50 face 19. The lower part of the section is complementary to the upper part (with the exception of the bottom section) so that all the sections receive each other and present a grain tight abutment on their inner faces. 55

At either end of each section, I provide a U shaped bar 20 fastened through the base of the U to the section by rivets 21. The ends of the U bar are bent around the end of the section and pass over to the angle irons 11 and 12 and are then hooked over the flanges thereof. By this arrangement, all the sections are maintained in their proper places in respect to each other and the angle irons form a guide for their vertical movements. It will also be noticed that as the angle irons are placed on the sides of the door posts, they are out of the way when the car is used for other merchandise.

On the bottom of the lower section and adjacent the ends thereof, I locate a pair of U shaped straps 22 and 23, which straddle the bottom of the section and are fastened thereto by bolts 24 passing through the section. Hooks 25 are pivotally connected to the ends of the bolts 24 at their outer extremities.

When the freight car reaches the terminal and it is desired to empty the car, a chain is connected across the hooks 25. A crane or other source of lifting power is attached to the chain and the door can be bodily lifted, the U shaped hooks 20 sliding along the angle irons 11 and 12. As the door is lifted, the hooks click past a pair of lock bars 26 pivoted on the door posts and riding against the flanges of the angle irons. When the bottom section has cleared the lock bars, the lifting force is released and the lock bars support the door in an elevated position, the majority of the grain in the meantime having run out through the opening below the door. The car is then tipped over on its side and the balance of the grain is removed.

If it is desired to store the door, the operator may re-connect the crane and lift the sections or he may do the work manually, lifting each section, one at a time, the sections passing around the curved, upper ends of the angle irons 11 and 12 and are then received between the upper flanges of the channel irons 13 and 14 and the webs 13'. The sections are then slid along the compartments 14' toward the centre of the car and all the first sections are passed down the vertical passages 16' where they are stored in a horizontal position in the lower compartments 15' while the latter sections are stored in a similar position in the upper compartments 14'. The arrangement is shown to advantage at 27 in Fig. 2.

In reference to the moving of the sections along the angle irons 11 and 12 to the storage position, it will be noticed, that due to the slope of the angle irons, the connections between the sections and the angle irons is very loose the

farther up the sections are lifted and due to this construction, the angle irons not only avoid the sill at the upper corner, but the loose play afforded, permit the sections to pass freely around the curve without binding.

From a consideration of Fig. 2, it will be observed that the sections in the lower compartments 15' cannot escape at the ends of the channels due to an upstanding bolt 28 carried at the ends of the lower flanges of the channel irons. The U shaped bars 20 on the sections in the upper compartments 14' are slightly below the position they should occupy to become re-attached to the angle irons 11 and 12 and accordingly, the jolting of the car over the rails 10 will not cause them to slide down the irons. On the other hand, the space below the angle irons to the web 13' is too small to permit them to pass underneath and accordingly, they are maintained in their stored position. When the 20 door is to be re-erected however, the operator will bring each section to a position in front of the ends of the angle irons 11 and 12, lift each section to re-hook the U bars to the said angle irons and they can then be slid down 25 into the doorway, the lock bars of course being released.

While I have shown the sections made from lumber, it will be appreciated that pressed metal or other suitable material could be substituted.

What I claim as my invention is:

In combination with a railroad freight car having opposing doorways with side door posts, a grain door construction therefore comprising vertical angle guides secured to the faces of the door posts remote from the door ways and positioned at a slight outward sloping angle theredown, a grain door adapted to be received against the car interior faces of the door posts comprising a multiplicity of individual sections 35 stacked one above the other in grain tight abutments and each of said sections provided at either end, on the car interior side with U shaped straps, said straps, bent around the ends 40 of the sections and hooked over the flanges of 45 the adjacent guides for vertical sliding movement of the sections thereon and such that the receding lower portion of the guides, through the straps, will hold the lower door sections in a grain tight engagement with the interior faces 50 of the door posts while the upper advancing portions of the guides, through the said strips, will loosely retain the upper door sections in position to be pressed into similar grain tight engagement with the door posts by the weight 55 of loading grain.

HENRY WILLIAM ETHELL.
